PAUL L. V. THIERY, OF NEWARK, NEW JERSEY, ASSIGNOR TO WM. B. KERR & CO.

DESIGN FOR A POCKET-BOX.

SPECIFICATION forming part of Design No. 24,791, dated October 29, 1895.

Application filed October 18, 1894. Serial No. 526,104. Term of patent 8½ years.

To all whom it may concern:

Be it known that I, PAUL L. V. THIERY, a citizen of the United States, residing at Newark, in the county of Essex and State of New Jersey, have invented a new and original Design for a Pocket-Box, of which the following is a specification.

The accompanying drawings represent a pocket-box embodying my design, and consists as shown in Figure 1, which is a perspective view of said box with the design displayed upon it in relief, and Fig. 2, which is a cross-section of said box.

The essential feature of my design consists of a pocket-box provided with the representation of a group of nude females and the mythological diety Satyr upon the bank of a stream, with a background of foliage and another group of female figures in the distance, as shown in the accompanying drawings.

In Fig. 1, D D D D are the female figures; E, the figure of the Satyr; F, the ground; G, the stream of water; H, the background, and I the group of females in the distance. The figure of the Satyr E is represented standing with one foot in the stream and the other on the bank and resisting the efforts of the females D D D D, who are endeavoring to force him into the water G. One of the females is represented in the act of signaling the group in the distance, who are also standing or reclining upon the bank of the stream.

What I claim is—

The design for a pocket box, substantially as herein shown and described.

In testimony whereof I affix my signature in the presence of two witnesses.

PAUL L. V. THIERY.
